UNITED STATES PATENT OFFICE.

JOHN KREHBIEL, OF KALAMAZOO, MICHIGAN.

VESTIBULE FOR CARS.

SPECIFICATION forming part of Letters Patent No. 417,567, dated December 17, 1889.

Application filed September 2, 1889. Serial No. 322,739. (No model.)

To all whom it may concern:

Be it known that I, JOHN KREHBIEL, a citizen of the United States, residing at Kalamazoo, in the county of Kalamazoo and State of Michigan, have invented certain new and useful Improvements in Vestibules for Railway-Cars, of which the following is a specification, reference being had therein to the accompanying drawings.

10 This invention relates to new and useful improvements in vestibule-cars; and the object of the invention is to do away with the flexible construction now in use and obtain the necessary self-adjustability with a rigid construction.

15 My invention consists in the peculiar construction and arrangement of parts whereby a rigidly-constructed vestibule is adjustably supported between the adjoining ends of two cars in such a manner that it will adjust itself to the relative movement of the cars without interfering, all as more fully herein-after described, and shown in the accompanying drawings.

20 Figure 1 is a plan view with the vestibule shown in horizontal section between the adjoining ends of two cars. Fig. 2 is a side elevation. Fig. 3 is a vertical central section. Fig. 4 is an end elevation of one car provided with its section of vestibule. Fig. 5 is a detached perspective view of one section of the vestibule.

25 A A are the two halves of the vestibule, each being constructed like the other and adapted to jointly form together a covered passage between the ends of the adjoining cars when coupled together in the usual manner. These vestibule-sections I construct in a rigid manner, preferably of style and ornamentation in keeping with the cars and in a light but substantial manner, preferably with a light steel frame.

30 Each section of vestibule consists of a floor *a*, sides *b*, provided with the usual doors *c*, and preferably a window *d* or glass paneling *d'* and a roof *e*. The two ends are open, or substantially so, one end being provided with flexible or hinged dust-guards *f*, (see Fig. 1,) which are adapted to close against the 35 ends of the cars, the other end being provided with a frame *h*, adapted to form a good bearing all around when the two sections are

coupled together, which is preferably accomplished by suitable coupling or locking devices, such as the rigid hooks *i* adapted to project into keepers in the opposite frame and be engaged by locking devices *j*, and by guide-pins engaging into corresponding recesses in the opposite frame.

40 The meeting ends of the vestibule-sections have suitable guides—such as the guides *K*—to bring them in proper apposition to each other when the cars are coupled and hold them when coupled from being accidentally displaced. I preferably provide the frames 45 or construct them with inwardly and outwardly projecting flanges *m*, (which on top and at the sides are beveled to shed the water off the joint,) and the object of which is to impart rigidity to the central portion of 50 the vestibule when the sections are jointed, so that the two sections together will form practically one structure only.

45 Each section of the vestibule is connected to its respective car in the following manner: Under the inner end of the floor in the center the vestibule-section has a pivotal sliding connection with the platform of any suitable construction which will admit of a certain play of the vestibule in the longitudinal direction of the car, and also permit it to tip freely in any direction. To accomplish this the vestibule-floor is raised high enough above the car-platform to admit of such free play.

50 As a form of the many joints which may be desired, I show in the drawings a pivot-bolt *o* secured to the under side of the vestibule-floor and engaging into a longitudinal socket or slot *p* in the car-platform, which allows the vestibule to tip to either side or end, and also 55 permits longitudinal displacement with more or less tendency to return to a normal position when free to do so. The opposite end of the vestibule I support on springs in any suitable manner free to allow the vestibule 60 to tip or to be displaced longitudinally. As a form of such support, I show the leaf-springs *v*, which bear against the under side of the vestibule-floor near the sides, and the tension of which is preferably so adjusted 65 that if the cars are uncoupled they will, under normal condition, support the weight of the vestibule on a bevel. A continuous floor is formed by means of a suitable floor-plate

55

s, pivotally secured to the vestibule-floor and forming a close joint against the car-floor. To prevent accidental displacement beyond the degree required by the circumstances, I provide certain stops—such as the stops *u* and chain *t*—on the platform.

10 The vestibule being constructed and arranged substantially as described and shown, it will be seen that while the vestibule is absolutely rigid the supports are in every way self-adjusting under the relative movement of the two adjoining cars, no matter in which direction. The lateral oscillations are easily compensated for by the yielding lateral supports and by the pivots which provide for sufficient lateral play to either side. The vertical movement is compensated for by the yielding supports and the longitudinal displacement by the longitudinal play of the 20 pivot.

15 It is well understood that with the present construction a great tensional resistance is maintained between the cars, which also may sometimes lessen the oscillations of the cars, transmitting them from one car to the other through the whole train and greatly increasing the friction of the cars on the rails in passing around curves, as the pivotal connection between the cars is greatly interfered with by 25 the vestibule. On my construction I avoid this difficulty, as I preserve the full freedom 30 of the pivotal connection between the cars; and it will be further observed that the variation between the ends of my vestibule and the ends of the cars are, and necessarily must be, of less magnitude than the variation in 35 the center of the vestibule, as in the present construction.

What I claim as my invention is—

40 1. In a vestibule-car, a vestibule constructed to form a rigid independent structure between two adjoining cars and provided with self-adjusting and yielding supports upon the platforms of the respective cars to permit of

the free relative movement of the two cars, 45 substantially as described.

2. A car-vestibule rigidly constructed in two separable halves and pivotally supported upon and free of the platform of two adjoining cars independent of the relative movement between the cars, substantially as described.

3. In a vestibule-car, a vestibule rigidly constructed in two separable like halves, each supported upon the platform of the car on a 55 sliding pivot, and yielding lateral supports under the floor of the vestibule, substantially as described.

4. In a vestibule-car, a vestibule rigidly constructed in two separable halves provided with coupling devices on their meeting faces 60 adapted to rigidly secure them together, of central pivotal sliding supports and lateral yielding supports on the supporting-platforms of the car, substantially as described.

5. In a vestibule-car, a vestibule constructed in two like halves separately secured together and forming an independent rigid structure between two adjoining cars and having self-adjusting supports upon the respective platforms of said cars, of coupling devices adapted to rigidly secure the two halves together, and false thresholds pivotally secured to the respective ends of the floor of the vestibule, substantially as described.

6. In a vestibule-car, a vestibule consisting of two like halves, each provided with supports *a b* upon the platform of the car, the coupling devices, the aprons, and the false threshold, substantially as described.

In testimony whereof I affix my signature, in presence of two witnesses, this 22d day of August, 1889.

JOHN KREHBIEL.
